CLAIM

The ornamental design for a frothing impeller as shown and described.

DESCRIPTION

FIG. 1 is a front left perspective view of a frothing impeller, shown in environmental use, showing my new design; FIG. 2 is a bottom left perspective view thereof, shown in environmental use;

FIG. 3 is a front view thereof, shown in environmental use;

FIG. 4 is a rear view thereof, shown in environmental use;

FIG. 5 is a left side view thereof, shown in environmental use;

FIG. 6 is a right side view thereof, shown in environmental use;

FIG. 7 is a bottom view thereof, shown in environmental use;

FIG. 8 is a front left perspective view thereof;

FIG. 9 is a bottom left perspective view thereof;

FIG. 10 is a front view thereof;

FIG. 11 is a rear view thereof;

FIG. 12 is a right side view thereof;

FIG. 13 is a left side view thereof;

FIG. 14 is a top view thereof; and,

FIG. 15 is a bottom view thereof.

The broken lines forming the base in the drawings illustrate environment only and forms no part of the claimed design.

1 Claim, 4 Drawing Sheets
